Primary Examiner — Joseph Kukella*Assistant Examiner* — Darryl J Dardenne(74) *Attorney, Agent, or Firm* — Riverside Law LLP(57) **CLAIM**

We claim the ornamental design for an infusion water bottle, as shown and described.

DESCRIPTION

FIG. 1 is a perspective view of an infusion water bottle showing my new design;

FIG. 2 is a left side view thereof;

FIG. 3 is a right side view thereof;

FIG. 4 is a front view thereof;

FIG. 5 is a rear view thereof;

FIG. 6 is a top view thereof;

FIG. 7 is a bottom view thereof;

FIG. 8 is an exploded perspective view thereof; and,

FIG. 9 is an exploded perspective view thereof.

The broken lines depict portions of the article that form no part of the claimed design.

1 Claim, 6 Drawing Sheets(56)
